UNITED STATES PATENT OFFICE.

DAVID McTAGGART, OF WORCESTER, MASSACHUSETTS.

WARP-BEAMING MACHINE.

SPECIFICATION forming part of Letters Patent No. 581,299, dated April 27, 1897.

Application filed September 21, 1896. Serial No. 606,475. (No model.)

To all whom it may concern.

Be it known that I, DAVID McTAGGART, a citizen of the United States, residing at Worcester, in the county of Worcester and 5 State of Massachusetts, have invented a new and useful Improvement in Warp-Beaming Machines, of which the following is a specification, accompanied by drawings representing so much of a warp-beaming machine embodying my present improvement as is necessary to clearly illustrate the nature of my invention and the manner in which the same is carried into effect.

Referring to the accompanying drawings, 15 Figure 1 represents a front view of a warp-beaming machine embodying my invention. Fig. 2 represents in perspective view a warp-beaming machine embodying my invention, the mechanism by which the warp-beam is 20 rotated having been omitted. Fig. 3 is a perspective view of my improved warp-beaming machine shown in perspective view, but with the pressure-roll in an elevated position. Fig. 4 is a central longitudinal sectional view of 25 the pressure-roll. Fig. 5 is a transverse sectional view of the pressure-roll and the central hooked arm of the framework by which the pressure-roll is supported, said section being taken on a vertical plane passing through 30 the center of the central hooked arm of the framework. Fig. 6 is an end view of the pressure-roll and a portion of the supporting-framework, showing the latch by which the pressure-roll is held from longitudinal movement in one direction when raised in the 35 position shown in Fig. 3. Fig. 7 is a central sectional view of the screw-actuated sliding block with which the suspension-rope is connected, the section being shown on line 77, 40 Fig. 8. Fig. 8 is a side view of the screw-actuated sliding block shown in sectional view in Fig. 7, and Fig. 9 is a perspective view of the flanged sleeve by which the free end of the pressure-roll-supporting frame is locked 45 in one of the supporting-stands.

Similar letters refer to similar parts in the different figures.

In Figs. 1, 2, and 3 of the accompanying drawings I have represented the warp-beam 50 and the pressure-roll with its supporting-frame as resting upon the upright stands A A' of the simplest form of construction,

but in the place of these stands any suitable framework can be employed to support the operating parts of the machine.

B denotes a warp-beam journaled in the stands A and arranged to be slowly rotated by any of the well-known mechanisms employed for that purpose, one of which is represented in Fig. 1, and consisting of a supporting-framework C, in which is journaled a shaft C', carrying a belt-pulley C², by which power is applied to the shaft, and a pinion C³, engaging a gear C⁴ upon a shaft C⁵, to which is attached a pinion C⁶, engaging a gear C⁷, attached to the warp-beam B.

As the warp-beam B is slowly rotated the warp-threads are drawn from a reel (not shown) and wound upon the barrel B' of the warp-beam and between the heads B² B² in 70 the usual and well-known manner.

At the side of the warp-beam is a rocking bar D, supported upon the upright stands A' A² or other suitable framework and held parallel with the axis of the warp-beam B. The 75 bar D is so held in its supporting-stand as to be capable of rocking freely and also of being raised into an elevated position, as shown in Fig. 3, with one end raised clear from one of the supporting-stands, while the opposite end 80 is held in the other stand, and I accomplish this as follows: One end of the rocking bar D terminates in a ball D', held in a circular socket D², formed on the upper end of the stand A'. The opposite end of the rocking bar D is provided with a circular journal D³, inclosed by 85 a flanged sleeve D⁴, which is held when the machine is in operation in the upper end of the upright stand A². The stand A² is provided with a circular hole D⁵ of the same diameter as the outer diameter of the sleeve D⁴, with an opening D⁶ of the diameter of the journal D³, so that when the journal D³ is dropped from the position shown in Fig. 3 through the opening D⁶ and the sleeve D⁴ is 90 moved lengthwise on the journal and inserted in the circular hole D⁵ the rocking bar D will become locked in a horizontal position in the stand A², but be capable of rotating freely within the sleeve D⁴ and socket D².

Attached to the rocking bar D are the arms E E' and central arm E², extending over the barrel of the warp-beam and provided with hooked ends E³, adapted to inclose about two-

thirds of the periphery of a pressure-roll F, which is inserted endwise within the hooked ends E³ of the arms, so as to be held parallel with the axis of the barrel B' of the warp-beam with its under side resting upon the barrel B' or upon the warp-threads as they are wound thereon. Each of the arms E E' E² are recessed at their hooked ends, as shown at E⁴, to receive the friction-rolls E⁵ E⁵, which 5 turn upon pins E⁶, held within the arms E E' E². The friction-rolls E⁵ E⁵ are arranged to bear against the periphery of the pressure-roll F, so as to reduce the friction upon the 10 pressure-roll and permit it to be rotated within the hooked ends of the arms by its frictional contact with the rotating warp-beam. 15

Above the central arm E^2 is a bar G , journaled in the arm G' , projecting upwardly from the central arm E^2 , and in an arm G^2 , attached 20 to the rocking bar D . The edges G^3 of the bar G form ways for a sliding block G^4 , which is traversed along the bar G by means of a rotating screw G^5 , journaled concentrically within the ends of the bar G and connected 25 with the sliding block G^4 by means of a screw or pin G^6 , held in the block G^4 and engaging the threads of the screw.

The sliding block G^4 carries studs G^7 , upon which are placed the friction-rolls G^8 , arranged
 30 to bear against the lower edge G^3 of the bar G , and the upper end of the block G^4 is pro-
 vided with a circular socket to receive a ball
 G^9 , forming a ball-and-socket joint.

35 G^9 is a pulley-block G^{10} , containing a pulley G^{11} to receive a wire cable G^{12} .

The wire cable G¹² has one end attached to the ceiling and passes around the pulley G¹¹ and over a pulley G¹⁴, suspended by a swivel-joint from the ceiling, and from the end of the wire cable I suspend the weights G¹⁵, so as to exert a lifting strain upon the bar G and connected framework carrying the pressure-roll F.

45 When the rocking bar D is held within the stands A' A² by a ball-and-socket joint at one end and by a flanged sleeve D⁴ at the opposite end, the strain exerted by the weights G¹⁵ will tend to rock the bar D and carry the pressure-roll F toward or away from the warp-beam, as determined by the position of the sliding block G⁴ with reference to the vertical plane passing through the axis of the rocking bar D. For example, if the sliding block G⁴ be moved along the bar G by the actuating-screw G⁵ to a position to the right of the vertical plane passing through the axis of the rocking bar D and opposite to the warp-beam, as represented in Figs. 1 and 5, then the weights G¹⁵ will tend to rock the bar G and increase the pressure of the roll F upon the warp as it is wound upon the warp-beam; but if the sliding block G⁴ is moved upon the same side of the rocking bar D as the warp-beam it will tend to rotate the rocking bar D in the opposite direction and lift the pressure-roll F off the warp. The amount of

pressure exerted upon the warp can therefore be varied by shifting the position of the sliding block G^4 along the bar G by rotation of the screw G^5 by means of a wrench or crank applied to the squared end G^a of the screw. 70

When the warp-beam has been filled, the flanged sleeve D^4 is withdrawn from the circular opening D^5 in the stand A^2 and the sliding block G^4 is moved along the bar G toward the pressure-roll F , causing the weights G^{15} to raise the end of the rocking bar D through the opening D^6 in the stand A^2 , lifting the pressure-roll F into the position represented in Fig. 3, thereby allowing free access to the warp-beam. When the pressure-roll is raised in an oblique position, as represented in Fig. 3, it is prevented from sliding endwise through the hooked ends of the arms $E E' E^2$ by means of a latch consisting of a plate H , pivoted at one end to the side of the arm E and carrying at its opposite end a projecting rod H' , to which is adjustably attached an arm H^2 , arranged to drop over the end of the pressure-roll E and hold it against gravity. Attached to the arm E is a plate H^3 , provided with a slot H^4 , through which the rod H' passes and serves as a guide for the free end of the pivoted plate H .

When the bar D is lowered into the position shown in Fig. 2, the pressure-roll F will lie upon the barrel B' of the warp-beam, filling the space between the heads B² B², and the lower end of the arm H² will rest upon and be held up by the head of the warp-beam.

The pressure-roll F is variable in length, in order to allow for any irregularity in the space between the heads B² B³ of the warp-beam, and it is also made in sections to allow its length to be adjusted approximately to the length of different warp-beams. The construction of the pressure-roll F is shown in central sectional view in Fig. 4 of the accompanying drawings, where I denotes the central portion of the roll, having at one end an extension-piece I', detachably attached to the central portion by a screw I², allowing the extension-piece I' to be exchanged for others of different lengths, in order to adapt the pressure-roll to different warp-beams. At the opposite end of the pressure-roll is a spring-actuated sliding section J, provided with a concentric hole J' at one end fitting upon and sliding over the reduced end J² of the central portion I. 105 110 115 120

The section J is acted upon by a spring or springs inserted between the end of the section J and the shoulder J³ on the section I.

In the construction shown in Fig. 4 I employ two springs J^4 and J^5 , separated by an annular collar J^6 midway between the end of the section J and the shoulder J^3 , and to the outer surface of the collar J^6 , I attach the thin sleeve J^7 with its ends overlapping the sections J and I , so as to cover the chamber containing the springs J^4 and J^5 and form a continuous surface. The sliding section J is held upon the section I and against the action of

the springs $J^4 J^5$ by means of a screw J^8 , which is screwed into the reduced end J^2 of the section I and is provided with a projecting flange J^9 , bearing against the recessed end of the 5 sliding section J. The sliding movement of the section J is limited in the opposite direction by means of an annular plate J^{10} , attached to a shoulder J^{11} in the recessed end of the section J, allowing a limited movement 10 of the section J equal to the distance between the annular plate J^{10} and the flange J^9 , a fraction of an inch being usually sufficient to allow for the usual variation in the distance between the heads $B^2 B^2$ upon opposite ends of 15 the warp-beam. The screw J^8 is provided with a squared end J^{12} , projecting through the annular plate J^{10} to receive a wrench and allow the length of the warp-beam to be varied by screwing or unscrewing the screw J^8 .

20 The operation of my improved warp-beaming machine is as follows: The warp-beam to be wound is placed in position, as represented in Fig. 3. The frame, consisting of the rocking bar D and arms E, E', and E'', supporting the pressure-roll F within their hooked ends, is then lowered from the elevated position shown in Fig. 3 to the horizontal position represented in Figs. 1 and 2, the end D^3 of the rocking bar D being locked within the stand A² by means 25 of the sliding flanged sleeve D⁴ in the manner already described. The sliding block G⁴ is then moved from the position shown in Fig. 3 to that shown in Fig. 2, so the strain of the weight G¹⁵ will be exerted to rock the bar D 30 and carry the pressure-roll F down upon the warp as it is being wound upon the warp-beam, the pressure being increased as the sliding block G⁴ is moved farther to the rear of the rocking bar D. The pressure-roll F, 35 when in the elevated position represented in Fig. 3, is held from being moved lengthwise within the frame by gravity by means of the latch, consisting of the pivoted plate H, rod H', and arm H², said arm overlapping the end 40 of the roll, as represented in Fig. 6. When the roll F is lowered into the position shown in Figs. 1 and 2 and inserted between the heads of the warp-beam, the arm H² rests upon the edge of the warp-beam head, lifting the pivoted plate H, allowing the pressure-roll to 45 drop upon the barrel of the warp-beam, filling the space between the heads. As the warp-beam rotates the space between the heads is liable to vary slightly, owing to the heads not 50 standing in parallel planes at right angles to the axis of the warp-beam, and this variation in the distance between the heads of the warp-beam is provided for by means of the sliding section J, which is crowded against the inner 55 side of the warp-beam head by the action of the springs $J^4 J^5$ and allows a slight contraction in the length of the warp-beam to correspond with the variation in the distance between the inner sides of the heads. As the 60 warp-beam is filled the pressure-roll F rises, rocking the bar D in the stands A' A².

When the operation of winding is completed, the sliding block G⁴ is moved forward of the rocking bar D or upon the same side as the pressure-roll F by means of the screw G⁵, 70 as shown in Fig. 3. The rocking bar D is released from the stand A² by sliding the flanged collar D⁴ out of the opening D⁵ and allowing the end D³ of the rocking bar D to be lifted through the opening D⁶ into the position represented in Fig. 3, allowing free access to the 75 warp-beam.

What I claim as my invention, and desire to secure by Letters Patent, is—

1. In a warp-beaming machine, the combination of a pressure-roll, a rocking frame in which said roll is held, a pair of supporting-stands upon which said rocking frame is supported at its ends, a ball-and-socket connection between one end of said frame and one 80 of said stands, and a sleeve in which the opposite end of said frame is journaled, said sleeve being detachably held by the other of said supporting-stands, substantially as described.

2. The pressure-roll F combined with a supporting-frame partially inclosing said pressure-roll, whereby it is held by its periphery so as to be capable of rotating and also of a slight longitudinal movement in said frame, 95 and a latch held by said frame and arranged to overlap the end of said pressure-roll and hold it against movement in one direction, substantially as described.

3. The combination of a rocking frame, a 100 pressure-roll held by said rocking frame and horizontally at one side of the axis of the frame, a bar attached to said frame transversely to and vertically above its axis and extending upon both sides of the vertical plane 105 containing the axis of said frame, a suspended weight and means for connecting said weight to said transverse bar upon either side of the vertical plane of the axis of said frame, whereby said weight is made to either lower or raise 110 the pressure-roll, substantially as described.

4. The combination of a rocking frame, a pressure-roll held by said frame, a bar attached to said frame, transversely to and above the axis of the frame, said bar extending upon both sides of a vertical plane containing the axis of said frame, stands by which 115 said rocking frame is supported and means for applying a lifting power to said transverse bar, whereby said frame is either rocked 120 or raised above its supporting-stands, substantially as described.

5. The pressure-roll F combined with a frame by which said roll is supported, said frame being capable of a rocking motion about 125 an axis parallel with the axis of said pressure-roll, a bar attached to said frame above said pressure-roll and transversely to the axis of said frame, and extending upon both sides of a vertical plane containing the axis of said 130 rocking frame, a sliding block adjustably held on said bar and a weight connected with said

block so as to exert an upward pull upon said bar and tend to rock said roll-supporting frame, substantially as described.

6. The combination of roll F, frame supporting said roll and capable of rocking about an axis parallel with the axis of said roll, a bar G attached to said frame transversely to the axis of said roll and said frame, a sliding block G⁴ adjustably held on said bar, a weight connected with said block to exert an upward pull and a screw journaled parallel to said bar and engaging said sliding block, substantially as described.

7. The pressure-roll F combined with a frame consisting of a rocking bar D, arms E, E' and E² supporting said roll, transverse bar G attached to said frame, sliding block G⁴, rolls G⁸, G⁹ carried by said block, a pulley-block G¹⁰ connected to said sliding block by a ball-and-socket joint, a weight connected with said pulley-block and exerting an upward strain on said pulley-block and a screw G¹³ by which said sliding block is adjusted along said transverse bar, substantially as described.

8. The combination of a roll F, a rocking bar D, arms E, E' and E² provided with hooked ends E³, said hooked ends partially inclosing said roll, stand A' having a ball-and-socket connection with one end of said bar D, stand A² provided with a circular opening D⁵ and an opening D⁶, a flanged sleeve D⁴ held in said stand A² and inclosing the opposite end of said rocking bar and a weight connected with said frame to exert an upward pull, substantially as described.

9. In a warp-beaming machine, the combi-

nation with a warp-beam of a rocking frame, a pressure-roll supported by said rocking frame by its periphery so as to rotate therein, said pressure-roll having a central portion as at I provided with a reduced portion as at J², a sliding section J capable of sliding on said reduced portion J², a spring between said sliding section and the central portion I of the roll and a screw J held in the reduced portion J² and provided with a flange J⁹ by which the motion of said section J, as actuated by said spring, is limited, substantially as described.

10. The combination in a warp-beaming machine, of the roll F and a supporting-frame, said roll F having a reduced portion J², sliding section J, collar J⁶ sliding on said reduced portion J², sleeve J⁷ attached to said collar, springs J⁴ and J⁵ placed on opposite sides of said collar and a screw J⁸ by which the movement of said sliding section J is limited, substantially as described.

11. The combination in a warp-beaming machine of a pressure-roll having a reduced portion J², sliding section J, collar J⁶, sleeve J⁷ attached to said collar, springs J⁴ and J⁵ on opposite sides of said collar, screw J⁸ held in the reduced portion J² of the roll, flange J⁹ and a plate J¹⁰ attached to the sliding section J with a space between said plate and said flange J⁹ to allow for the movement of said section J, substantially as described.

Dated this 10th day of September, 1896.
DAVID McTAGGART.
